UNITED STATES PATENT OFFICE

1,953,788

ELECTRIC CIRCUIT BREAKER

Paul Thieme, Kopenick, Wendenschloss, Germany, assignor to General Electric Company, a corporation of New York

Application January 14, 1933, Serial No. 651,777
In Germany April 20, 1932

5 Claims. (Cl. 200—150)

My invention relates to electric circuit breakers and more particularly to circuit breakers of the type utilizing an arc extinguishing liquid.

A principal object of my invention is the provision of an improved circuit breaker of the aforesaid type which is simple, rugged and compact in construction, efficient in operation and comparatively free of objectionable liquid throw during normal operation.

10 My invention will be more fully set forth in the following description referring to the accompanying drawing, and the features of novelty which characterize my invention will be pointed out with particularity in the claims annexed to 15 and forming a part of this specification.

Referring to the drawing, Fig. 1 is an elevational view, partly in section of a part of a circuit breaker embodying my invention and Fig. 2 is a similar view showing a modified form of 20 my invention.

The circuit breaker illustrated by way of example comprises relatively movable contacts including a stationary socket contact 1 and a co-acting movable rod contact 2. The contacts 25 co-act within a pressure confining chamber 3 in which the stationary contact is suitably mounted. The pressure confining chamber 3 may be formed in any suitable manner as by a cylindrical member 4 closed at one end as at 5 and provided at its opposite end with an exhaust opening 30 which is arranged to receive the movable rod contact 2. The pressure confining chamber likewise contains an arc extinguishing liquid as hereinafter described.

35 In a circuit breaker of this type it will be apparent that separation of the contacts for the purpose of interrupting a high tension power circuit causes intensive arcing which tends to vaporize and expel liquid from the chamber 3 due 40 to the high pressure generated therein. For the purpose of receiving the exhaust liquid and for aiding interruption of the circuit, there is provided a casing 7 which is in communication with the exhaust opening 6 so as directly to receive 45 liquid expelled from the chamber 3 during circuit interruption. The casing 7 may be composed of a suitable insulating material and is provided with an opening 4' in which the cylindrical member 4 is secured. An arc extinguishing liquid 8, 50 as water or oil for example, partly fills the casing 7 so as completely to cover the exhaust opening 6 of the pressure confining chamber.

55 For the purpose of reducing and minimizing the expulsion of liquid during circuit interruption the casing 7 is provided with a deflecting

wall or partition 9, forming with the casing a second chamber 10 through which the movable rod contact is operable. The deflecting wall 9 is disposed substantially opposite the exhaust opening 6 and is inclined with respect to the exhaust of liquid therefrom so as to deflect the liquid into the lateral extension 7' of the casing 7 as diagrammatically illustrated. It will be noted that the longitudinal axis of the casing 7 is substantially perpendicular to the longitudinal axis of the pressure confining chamber 3, the deflecting wall 9 being inclined approximately 45° to each axis so as to deflect liquid expelled from said chamber across the arc drawn between the contacts and longitudinally of the casing 7. 70 The deflecting wall 9 is provided with an opening 9' for receiving the movable contact, the casing 7 likewise being provided with an aligned opening 2' for said contact.

When the circuit is to be interrupted, the rod 75 contact 2 is moved upwards by suitable operating means, not shown, with the result that the arc is drawn between contacts 1 and 2 within the chamber 3. The resulting pressure causes expulsion of liquid from said chamber in the direction of the 80 arc when the rod contact has cleared the exhaust opening, the main part of the liquid being deflected by the wall 9 into the lateral extension of the casing 7 and across the arc formed between the contacts. It will be apparent that the deflection of liquid through the arc aids interruption thereof in the event that the arc is not already extinguished shortly after the rod 2 has cleared the exhaust opening. Upon further opening 85 movement of the contact 2 expelled liquid is free to enter the second chamber 10 through the opening 9' which is of small cross sectional area as compared with the deflecting wall. The amount of liquid directed through this opening is therefore not large and is collected in the chamber 10 90 so that the final expulsion of liquid from the circuit breaker is negligible.

Fig. 2 illustrates a modification wherein the deflecting wall 9 is provided with a portion 11 which is spaced from the upper wall of the casing 7 so 100 as to provide communication as at 11' between the chamber 10 and the interior of the casing 7. The operation is substantially the same as described above except that when the rod contact 2 is in the position shown during circuit interruption, pressure within the chamber 10 due to 105 expulsion of liquid through the opening 9' may be relieved by way of the opening 11'. Accordingly there is little or no tendency for liquid to escape through the opening 2' in the casing 7. 110

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States, is:—

1. An electric circuit breaker comprising relatively movable contacts, a pressure confining chamber containing an arc extinguishing liquid in which one of said contacts is disposed, the co-acting contact being movable into and out of said chamber through an exhaust opening therein, a 10 casing in communication with said exhaust opening through which said movable contact is withdrawn upon separation of said contacts, and a partition forming with said casing a second chamber through which said movable contact is operable, said partition being substantially opposite and inclined in substantially the same direction with respect to the exhaust of liquid from said pressure confining chamber during circuit interruption.
2. An electric circuit breaker comprising relatively movable contacts, a pressure confining chamber containing an extinguishing liquid in which said contacts are arranged to separate, said chamber having an exhaust opening through 30 which one of said contacts is drawn during circuit interruption, a casing having a lateral extension into which liquid from said chamber may exhaust, and a partition substantially opposite said exhaust opening forming a second chamber 35 through which the last named contact is operable, said partition having an opening for said contact and being inclined in substantially the same direction with respect to the exhaust of liquid from said pressure confining chamber during 40 circuit interruption so that said liquid is deflected across the arc drawn between said contacts and into said lateral extension.
3. An electric circuit breaker comprising relatively movable contacts, a pressure confining 45 chamber containing an arc extinguishing liquid in which one of said contacts is disposed, the co-

acting contact being movable into and out of said chamber through an exhaust opening therein, a casing into which liquid may exhaust through said opening, the longitudinal axis of said casing being substantially perpendicular to the longitudinal axis of said pressure confining chamber and a partition forming with said casing a second chamber through which said movable contact is operable, said partition being substantially opposite said exhaust opening and inclined in substantially the same direction so as to deflect liquid expelled from said chamber longitudinally of said casing.

4. An electric circuit interrupter comprising a stationary contact and a movable contact, a pressure confining chamber containing an arc extinguishing liquid in which said contacts coact, said stationary contact being disposed in said chamber and said rod contact movable through an exhaust opening therein, a casing having a lateral extension into which liquid from said chamber may exhaust through said opening, and a partition within said casing having a substantially plane portion disposed above said opening and inclined with respect thereto so as to deflect liquid expelled from said chamber into said lateral extension and across the arc formed between said contacts.

5. An electric circuit interrupter comprising relatively movable contacts and a pressure confining chamber containing an arc extinguishing liquid in which said contacts are arranged to separate, said chamber having an exhaust opening through which one of said contacts is drawn during circuit interruption, a casing having a lateral extension in communication with said exhaust opening, and a substantially plane deflecting wall disposed above and inclined with respect to said exhaust opening forming a second chamber through which said movable contact is operable, 115 said wall having an aperture for receiving said movable contact and being spaced from the wall of said casing at one end to provide communication between said second chamber and casing.
